[21] Appl. No.: 70,476

I claim the ornamental design of a garden tag, as shown and described.

[22] Filed: May 8, 1997

DESCRIPTION

[51] LOC (6) Cl. 19-08

FIG. 1 is a perspective of the invention;

[52] U.S. Cl. D8/1

FIG. 2 is a front view of the invention;

[58] Field of Search D20/22-23, 28;
40/316-324, 299; D8/1

FIG. 3 is a typical side view of the invention; and,

FIG. 4 is a top view of the invention.

The bottom view would be identical to the top view of FIG. 4.

The broken lines shown in FIGS. 1 and 2 are for illustrative purposes only and form no part of the claimed design.
